UNITED STATES PATENT OFFICE.

LOUIS HAUBNER, OF LONDON, ENGLAND.

ROTARY INTERNAL-COMBUSTION ENGINE.

1,043,589.

Specification of Letters Patent.

Patented Nov. 5, 1912.

Application filed March 30, 1912. Serial No. 687,339.

To all whom it may concern:

Be it known that I, LOUIS HAUBNER, a subject of the King of England, residing at London, in the county of Middlesex, England, have invented certain new and useful Improvements in Rotary Internal-Combustion Engines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention has reference to rotary internal combustion engines, of the kind in which the cylinders are radially disposed and rotate in one direction and the shaft in the other direction, and the two parts are geared with a stationary part, while each of the cylinders is provided with a comparatively large single inlet and exhaust valve, and fitted with an independent fuel muzzle connected with the supply through a tubular shaft, while the invention also has reference to rotary internal combustion engines, having radially disposed cylinders each fitted with a valve for controlling the inlet and exhaust, and cams and levers for operating the valve from the shaft.

One of the objects and effects of the invention, is to provide an improved arrangement of parts particularly serviceable in connection with aeronautical machines provided with propellers, and enable propellers having blades of maximum pitch to be employed to advantage.

Another object and effect is to provide an improved engine of the kind referred to, with an improved arrangement of parts of improved construction whereby the parts are easily and quickly assembled and taken apart.

Other objects and effects of the invention are hereinafter set forth in the following description.

Under this invention the valve with which each cylinder is provided and which serves to open and close the port for both the inlet and exhaust, is positively controlled by a cam or eccentric, and this valve is not only positively controlled but is so actuated that it is held open during the inlet and exhaust strokes of the piston, and thereby the pressure within the cylinder is equiva-

lent to atmospheric pressure during the time of such strokes. Further, the fuel is injected into the cylinders thereby and enables a carburetor to be dispensed with. 60

Other features which may be mentioned as forming part of the invention, comprise conveying the fuel from the fuel tank through the medium of a chambered sleeve fitted with plugs to prevent leakage, and a 65 casing comprising two halves which serve to inclose the crank shaft, the gearing for effecting the rotation of the cylinders in an opposite direction to that of the shaft, the cams or eccentrics for positively actuating 70 the valves of the cylinders and the ball bearings of the casing and cylinders.

A rotary internal combustion engine constructed according to this invention is hereinafter described with reference to the accompanying drawings, in which,

Figure 1 is a horizontal sectional view of the engine. Fig. 2 is a sectional elevation, and Fig. 2^a an under plan, of a compound plug. Fig. 3 is a side elevation partly in 80 section of a piston ring.

In the drawings, *a* designates the shaft of the engine, and *a*¹ the crank portion thereof, which is disposed in the crank casing *b*, of the engine, and is connected with the pistons *c*, of cylinders *d* by a compound crank head *e*, which is adapted to receive the inner ends of the connecting rods *f* to which the crank head *e* is connected. The outer end of each of the cylinders *d* is fitted with 90 a valve *g*, which serves to control the inlet of air, and the outlet of spent gases through the port *g*¹ formed in the end of the cylinder *d*. The valves *g* and ports *g*¹ are of comparatively large size, and the valves are actuated through the medium of cam members *h* and rings disposed on the cams *h*. The rings *h*¹ are adjustably connected with levers *i* which are pivotally mounted at *i*¹ and serve to support the valves *g* from a pivot 95 pin *g*². Rods *i*² which serve to connect the cam rings *h*¹ with the levers *i*, are pivotally connected at *i*² to the levers *i*, and are also adjustable longitudinally at this end, through the medium of a nut *i*³ in the pivot connection *i*², and the screw threaded end of the rod *i*². A convenient means of connecting the rods *i*² with the cam rings *h*¹ is shown at *h*². 100

The pistons *c* are mounted within the cylinders *d*, and the connecting rods *f* are connected to the crank *a*¹ by pins *c*¹. The

1   5   10   15   20   25   30   35   40   45   50   55   60   65   70   75   80   85   90   95   100   105   110   115   120   125   130

pistons *c* are each provided with a packing ring *c*² shown to an enlarged scale in Fig. 3. These rings *c*² comprise enlarged portions *c*³, adapted to take into annular recesses formed in the outer surfaces of the pistons *c*, and gradually reduced portions *c*⁴, the latter being reduced more or less to a knife edge, and are adapted to project beyond the ends of the pistons in such a manner that on the compression or explosion of the charges in the cylinders, these reduced portions are pressed outwardly against the inner surfaces of the cylinder *d*, and thereby prevent any leakages past the pistons, and wasting of the compressed charge, either during the compression of the same, or when firing takes place.

It is known in connection with internal combustion engines for high speeds, that the cylinders, owing to their light structure, and to the different temperature of one part relatively to the other part, that the cylinders when in use, are not exactly of circular forms, in cross section, being distorted by such conditions, and by the strain and other effects thereon; further, the pistons and the known forms of rings employed in connection therewith are not so constructed as to give and take to the slight variations in the forms of the cylinders,—due to the distortion by the effects previously mentioned,—and thus leakages occur, especially with engines for high speeds; but by the employment of rings as herein described with reference to the drawings, these leakages are entirely obviated.

Piston rings constructed as above described, with reference to Fig. 3, are easily pressed out against the inner surfaces of the cylinders *d*, and enable a gas tight, yet working fit to be obtained, and prevent any losses during the working of the engine by leakages or the like above referred to. In constructing such a piston ring, it is cut through as shown at *c*⁵ (Fig. 3), and such cut is soldered together, and after this has been effected, the ring is fashioned to the form shown in the drawings, that is, it is turned or otherwise shaped, with the enlarged portion *c*³, and reduced portion *c*⁴. After the ring has been produced in this manner, and has been fitted in position, the soldered portion *c*⁵ is heated, and the ring allowed to spring open, and thus enable a gas tight fit to be obtained.

As previously stated, the cylinders are adapted to rotate in the direction opposite to that of the shaft, and for this purpose the crank casing *b* is fitted with planet wheels *j*, which are carried by the pins *j*¹, fixed in the crank casing *b*. Each of the planet wheels engages or gears with a stationary sun wheel *k* and a rotary sun wheel *l*. The stationary sun wheel *k* is connected to a sleeve *m* which is fixed to the general framing *n* of the en-

gine. This framing *n*, is stationary, and thus when the pistons *c* are actuated, and the shaft *a* rotated, the rotary tooth wheel keyed thereto, serves to impart rotary motion to the toothed wheel *j*; this has for effect to rotate the cylinders and parts connected therewith, in a direction opposite to that in which the shaft rotates, such rotation being obtained through the toothed or planet wheels *j* engaging with the stationary sun wheel *k*. It will be obvious that this gearing may vary and have for effect to vary the number of strokes of the piston for each revolution of the engine, and the shaft; although in the construction illustrated, each cylinder is caused to complete one revolution around the axis of the shaft in one direction, and the shaft a complete revolution in the opposite direction, to a complete cycle of operations, such cycle being a four stroke cycle of the known kind.

The sleeve member *m* has a passage *m*¹ formed in it, and this passage at one end, is arranged in communication with a connection *m*² which is carried in the general framing of the engine, and is connected with a tube *m*³ and a source of supply of the liquid fuel such as a petrol tank. The opposite end of the passage *m*¹ communicates with a circular recess or chamber *o*, formed in a rotary member *o*¹, and arranged in communication with supply conduits *o*² connected by detachable connecting devices *o*³ with the compound plugs previously referred to, and particularly shown in Figs. 2 and 2^a. These compound plugs have liquid fuel orifices *o*⁴ fitted with snifting valves *p*, lightly held against their seats *p*¹ by spring members *p*², the tension of which is adjustable by means of nuts *p*³.

Adjacently to the front of each of the snifting valves *p*, are disposed the contact points *q* of the sparking device, these points being connected with the wire or rod *q*¹ passing through the insulating plug *q*², secured in the compound plug by means of a nut *q*³. The contact points are connected through the wire or rod *q*¹, and a terminal member *q*⁴, with the lead *q*⁵, which is connected with a contact plate *q*⁶ carried by the rotary member *o*¹. The magneto (which is not shown) is suitably connected with a brush contact device *r*, which is preferably spring pressed, and is carried by the general frame *n* and adapted to bear against the contact plate *q*⁶ previously referred to. The rotary member *o*¹ is rendered liquid tight on the sleeve *m* by means of packing plugs *o*⁵.

The cylinders and other rotary portions of the cylinders are carried on ball bearings *s* disposed on the shaft *a*, while the cam members *h* are disposed in the casing *b*² forming a part of the crank casing, and provided with apertures *b*⁸ for the passage of the rods connecting the valve levers with the cam

ings. This casing b^2 is fitted with an end over b^4 for inclosing the parts.

The crank casing b is preferably composed of two halves or side portions which are bolted together by means of bolts occurring between each of the cylinders, so that the various parts of the engine can be easily and quickly mounted in position on the shaft a , and at the same time such members or portions are of a relatively small number. It will be seen in Fig. 1 that each cam member or portion is adapted to actuate two diametrically disposed valves.

What is claimed is:

5. An internal combustion engine comprising a shaft journaled for rotation, a cylinder mounted for rotation about the axis of the shaft, means operatively connecting the cylinder with the shaft to rotate the shaft in the one direction as the cylinder rotates in the opposite direction, a piston slidably mounted in the cylinder, said cylinder having at its outer end a combined air inlet and exhaust port and a full inlet port, a combined air inlet and exhaust valve mounted in the cylinder and adapted to close the combined air
